UNITED STATES PATENT OFFICE.

JOHN BEIER, OF WHEELING, WEST VIRGINIA.

DESIGN FOR PLUG-TOBACCO.

SPECIFICATION forming part of Design No. 19,453, dated December 3, 1889.

Application filed September 27, 1889. Serial No. 325,337. Term of patent 7 years.

To all whom it may concern:

Be it known that I, JOHN BEIER, a citizen of the United States, residing at Wheeling, in the county of Ohio and State of West Virginia, have invented and produced a new and original Design for Plug-Tobacco, of which the following is a specification, reference being had to the accompanying drawing, forming a part thereof, which represents a plug of tobacco in rectangular form having a surface ornamentation representing a series of bell-shaped sections and half-sections, in general outline representing a full section of a bell and half-section of same.

15 The design consists of a representation of a plug of tobacco having a surface ornamentation representing a series of bell-shaped sections and half-sections of the same.

A represents a plug of tobacco in rectangu-

lar form, and B represents sections thereof in 20 outline in the form of a full vertical cross-section of a bell.

C C represent the half-sections having the inner line bell-shaped with the outer edge, a straight line square with the base, presenting 25 to the eye a plug of tobacco in rectangular form in outline with intermediate transverse lines having bell shape.

I claim—

The design for plug-tobacco having a general outline of rectangular form, with a surface ornamentation of dividing lines representing the general outlines of a bell and a half-bell or half-sections of the same, as shown.

JOHN BEIER.
